CLAIM

The ornamental design for a tester for USB data cables as shown and described.

DESCRIPTION

FIG. 1 is a front, left and top perspective view of a tester for USB data cables, showing my new design.

FIG. 2 is a rear, right and top perspective view thereof.

FIG. 3 is a rear, right and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof.

FIG. 10 is an enlarged view of detail 10 in FIG. 1.

FIG. 11 is an enlarged view of detail 11 in FIG. 1.

FIG. 12 is an enlarged view of detail 12 in FIG. 1.

FIG. 13 is an enlarged view of detail 13 in FIG. 1.

FIG. 14 is an enlarged view of detail 14 in FIG. 2.

FIG. 15 is an enlarged view of detail 15 in FIG. 3; and, FIG. 16 is another front, left and top perspective view of the tester for USB data cables of FIG. 1 shown with environment.

The dashed broken lines depict portions of the tester for USB data cables that form no part of the claimed design. The dot-dash broken lines in FIGS. 1-3 and 10-15 depict the boundaries of the enlargements and form no part of the claimed design. The additional dashed broken lines shown in FIG. 16 depict environmental structure and form no part of the claimed design.
